UNITED STATES PATENT OFFICE

2,555,379

BREECHBLOCK LOCK FOR FIREARMS

Clarence E. Simpson, Springfield, Mass., assignor
to the United States of America as represented
by the Secretary of War

Application June 7, 1946, Serial No. 675,124

12 Claims. (Cl. 89—186)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to a firearm of the semi-automatic type.

Most firearms of the semi-automatic type which utilize a comparatively large caliber high power cartridge are of rather ponderous and complicated construction and generally are provided with a fixed barrel precluding the possibility of replacing such barrel in the field. Obviously such firearms cannot be readily transported and further these firearms would require a comparatively large mount to support the weight of such firearm. Another disadvantage with most firearms of the type above mentioned is that an excessively long recoil movement of the bolt is required for the ammunition feeding cycle. Furthermore, the ammunition utilized in such firearms is generally not conveniently carried in easily handled clips thus making loading of the firearm somewhat cumbersome.

Accordingly, it is an object of the this invention to provide an improved large caliber, semi-automatic firearm having a comparatively short recoil stroke.

Another object of this invention is to provide a firearm having a readily removable barrel to permit replacement of such barrel in the field.

Still another object of this invention is to provide an improved firearm action wherein the barrel and breech mechanism recoil rearwardly in locked relation.

Another object of this invention is to provide an improved semi-automatic firearm adapted to utilize ammunition contained in conveniently handled strips, such ammunition being aligned in the feedway by mechanical means independent of the recoiling members of the firearm.

Another object of this invention is to provide a large caliber military firearm that readily disassembles into two major assemblies for ease in transporting.

The specific nature of the invention as well as other objects and advantages thereof will clearly appear from a description of a preferred embodiment as shown in the accompanying drawings in which:

Fig. 1 is a longitudinal sectional view of the rear half of the firearm.

Fig. 2 is a side elevational view of the forward half of the firearm shown partly in cross-section.

Fig. 3 is a top elevational view of the rear half of the firearm.

Fig. 4 is a top elevational view of the forward half of the firearm.

Fig. 5 is a left side elevational view of the rear half of the firearm.

Fig. 6 is a left side elevational view of the front half of the firearm.

Fig. 7 is a detailed view shown partly in longitudinal section of the firearm with the breech mechanism in the closed position immediately after firing a cartridge.

Fig. 8 is a view similar to Fig. 7 but with the action and barrel in the extreme recoiled position.

Fig. 9 is a view similar to Fig. 8 but with the barrel unlocked from the breech mechanism and shown nearly in battery position.

Fig. 10 is a view similar to Fig. 9 but with the breech block in the bottom position on the carrier with a round contained in the breech block ready to enter the barrel chamber as the breech mechanism goes into battery.

Fig. 11 is a side elevational view of the left hand side plate illustrated in an upside down position showing the various cuts on the interior thereof.

Fig. 12 is a cross sectional view taken along the line 12—12 of Fig. 11.

Fig. 13 is a cross sectional view taken along the line 13—13 of Fig. 11.

Fig. 14 is a cross sectional view taken along the line 14—14 of Fig. 11.

Fig. 15 is a side elevational view of the right hand side plate showing the various cuts on the interior thereof.

Fig. 16 is a cross sectional view taken along the line 16—16 of Fig. 15.

Fig. 17 is a rear end elevational view of the fire-arm arm.

Fig. 18 is a detail view of the face of the breech block showing the location of the cartridge positioning detents.

Fig. 19 is a detailed top elevational view of a cartridge strip contained in the feedway of the firearm.

Fig. 20 is an enlarged cross sectional view taken along the line 20—20 of Fig. 19.

Fig. 21 is a cross sectional detail view taken along the line 21—21 of Figs. 19 and 20.

Fig. 22 is a cross sectional view taken along the line 22—22 of Fig. 20.

Fig. 23 is a side elevational detail view of the breech block showing the locking lugs on the side thereof.

Fig. 24 is a cross sectional view taken along the line 24-24 of Fig. 23 showing the T-shaped rib on the inclined arm of the breech block.

Fig. 25 is a sectional view taken along the line 25-25 of Fig. 23.

Fig. 26 is a cross sectional view taken along the line 26-26 of Fig. 23.

Fig. 27 is an enlarged detail view shown in longitudinal section of the sight mount elevating mechanism taken along the line 27-27 of Fig. 5.

Fig. 28 is a front end elevational view of the forward bottom plate.

Fig. 29 is a side elevational view of the feedway.

Fig. 30 is a side elevational view of the rear spacer.

Fig. 31 is an end elevational view of the rear bottom plate.

Fig. 32 is a top elevational view of the rear bottom plate.

Fig. 33 is a longitudinal sectional detail view of the breech mechanism retaining mechanism utilized for securing the breech mechanism in a partially retracted position.

Fig. 34 is a top elevational detail view of the sear releasing wedge-like member.

Fig. 35 is a top elevational view of the trigger.

Fig. 36 is a longitudinal sectional enlarged detail view of the sear release mechanism mounted on the firearm.

Fig. 37 is a cross sectional view taken along the line 37-37 of Fig. 36 showing the safety lock.

Fig. 38 is a detail view of the T-shaped plunger utilized in the sear release mechanism.

Fig. 39 is a top elevational view of the sear illustrating the sear tang.

Fig. 40 is a cross sectional view taken along the line 40-40 of Fig. 10 showing the T-slot in the carrier for mounting the breech block.

Fig. 41 is a side elevational detail view of the front spacer.

Fig. 42 is an enlarged detail view shown partly in longitudinal section of the barrel support illustrating the manner in providing clearance to facilitate removal of the barrel from the firearm.

Fig. 43 is a side elevational detail view of the operating slide.

Fig. 44 is an enlarged detail side elevational view showing the stop secured to the inclined arm of the breech block.

Fig. 45 is a detail fragmentary rear end view of the assembled breech block and carrier.

Fig. 46 is a fragmentary longitudinal sectional view of the assembled breech block and carrier illustrating the position of the firing pin and hammer.

Fig. 47 is an enlarged sectional view taken along the line 47-47 of Fig. 18.

Fig. 48 is a top elevational view of the carrier slide.

Fig. 49 is a rear end elevational view of the barrel extension illustrating the locking lugs and guide ribs thereon.

Fig. 50 is a side elevational view of the right hand feedway mounting bracket.

Fig. 51 is a side elevational detail view of the cartridge stop pawl.

Fig. 52 is a side elevational detail view of the feedway retaining pin illustrating the locking notch thereon.

Fig. 53 is a side elevational detail view of the locking spring utilized to secure the cartridge strip actuating tape within its cylindrical housing.

Fig. 54 is an enlarged detail longitudinal sectional view showing the operating slide contacting the firing pin retracting lever utilized for rais-

ing the hammer from the firing pin to eliminate breakage of the firing pin tip when opening the action of the firearm.

The firearm to be described in more detail 5 comprises essentially an open receiver having suitable ways on which is mounted a breech block and breech block carrier. The barrel of the firearm is readily detachable from such firearm and is supported at the forward end of the receiver by a suitable barrel support. The barrel screws into a threaded barrel extension. In the closed or breeched position, the breech block and barrel extension are held in locked relation by suitable locking lugs. A hydraulic recoil and counter-recoil mechanism is contained within a cylindrical tube extending forwardly of the receiver to check the recoil and counter-recoil forces of the firearm.

The forward portion of the barrel rests in a 20 front barrel support mounted on the end of the hydraulic cylinder tube. The cartridges are contained in strips which are fed into the feedway of the firearm and such feedway is mounted transversely across the top of the breech end of 25 the barrel. The cartridges are arranged to be withdrawn from the cartridge strip by a T-slot in the breech block. The cartridge strip is fed across the feedway by a spring actuated mechanism.

Referring to the drawings wherein similar characters refer to similar parts, there is shown 30 in assembled relation in Figs. 1, 2, 3, 4, 5, and 6 a firearm embodying this invention. A receiver 1 is provided to support the elements of the fire- 35 arm. The receiver 1 comprises two parallel side plates 2 and 3 separated at the rear and forward ends respectively by a rear spacer 4 and a front spacer 5. A rear bottom plate 6 and a forward bottom plate 7 are secured to the bottom edges 40 of side plates 2 and 3 as will be presently de- scribed. The rear spacer 4 (Figs. 1 and 30) comprises a substantially rectangular block which has formed thereon an integral rearwardly projecting cylindrical boss 9. An axial hole 10 is provided in the boss 9 which passes through the block portion of spacer 4. The hole 10 is of reduced diameter as shown at 10a where such hole emerges from the forward face of rear spacer 4. Boss 9 is provided with threads 11 on the outer periphery thereof to receive a buffer cap 12. Such buffer cap retains a buffer mechanism within hole 10 as will be later described. An integral vertical rib 13 is provided on each side of spacer 4 (Figs. 3 and 30) which engages corre- 50 sponding vertical grooves 14 provided on the rear inside edge of each side plate 2 and 3. The side plates 2 and 3 are secured to the rear spacer 4 as by screws 15.

As previously mentioned, the forward ends of 60 side plates 2 and 3 are secured in spaced relationship by the front spacer 5 (Figs. 4 and 41), such spacer comprising a substantially rectangular block. An integral cylindrical boss 18 extends forwardly from the front face of spacer 5, the exterior of which is provided with threads 19 for a purpose to be described. An axial hole 20 is provided in boss 18 and extends through spacer 5 for a purpose to be described later. Front spacer 5 is also provided with two oppositely dis- posed, integral, vertical ribs 17 which engage suit- 65 able vertical grooves 21 on the inside surfaces of side plates 2 and 3. Side plates 2 and 3 are se- cured to the front spacer 5 as by screws 22.

The rear bottom plate 6 (Figs. 1, 31 and 32) 70 essentially comprises a long narrow channel

shaped member. On each side of rear bottom plate 6 there is provided an integral horizontal projecting rib 23. The rib 23 engages corresponding horizontal grooves 24 in side plates 2 and 3 to securely position bottom plate 6 to such side plates. The forward end of rear bottom plate 6 slopes downwardly as shown at 25 (Figs. 1 and 31). An upstanding lug 26 is centrally provided on the downwardly inclined end 25 of rear bottom plate 6 and a downwardly sloped cam surface 27 is provided on the forward face of such lug for a purpose to be described. Somewhat to the rear of the downwardly sloped end 25 of rear bottom plate 6, two integral, inwardly projecting, oppositely disposed lugs 28 are provided to pivotally mount a carrier latch 100 to be later described. A transverse hole 29 is provided in each lug 28, such holes being counterbored on their inner ends as shown at 30. Bottom plate 6 is secured to side plates 2 and 3 by screws 31.

The forward bottom plate 7 is likewise a channel shaped member. A suitable integral horizontal rib 32 (Fig. 28) extending the length of bottom plate 7 is provided on each side of such bottom plate and engages suitable horizontal grooves 33 on the bottom edge of each side plate 2 and 3 (Figs. 11 and 15). Bottom plate 7 is secured to side plates 2 and 3 by screws 34.

Near the upper edge of each side plate 2 and 3, there is provided a longitudinal groove-like guideway 35 to slidably support a barrel extension 150 to be described. The forward portion 35a of each guideway 35 is cut through to the top of side plates 2 and 3 to permit the barrel extension to be readily removed from such side plates in a manner to be later described. Somewhat below the longitudinal guideway 35 an integral longitudinal rib 36 is provided on each of the side plates 2 and 3 and terminates just short of the forward end of such side plates. Near the lower edge of side plate 2 underneath rib 36 a longitudinal T-slot 37 is provided to slidably mount an operating slide 175 to be described.

A tubular member 38 internally threaded at its rear end is horizontally secured to the boss 18 of front spacer 5 by screwing such tube onto threads 19 of boss 18. The tube 38 houses a recoil spring and a hydraulic recoil and counter-recoil mechanism which is fully described in my patent application, Serial No. 439,658, filed April 20, 1942, now U. S. Patent No. 2,364,103.

To support a barrel 50 of the firearm, a front barrel bearing support 39 (Figs. 2 and 42), is secured to the forward end of tube 38 by threads 40. The front barrel support 39 comprises a cylindrical end cap 41 and an integral upwardly projecting lug 42. A longitudinal hole 43 is provided in lug 42 to admit the forward end of barrel 50. To facilitate insertion and withdrawal of barrel 50 from front barrel support 39, the upper rear surface of hole 43 is enlarged and tapered slightly as shown at 44 while the lower opposite surface of hole 43 is likewise slightly enlarged and tapered as shown at 45. Such enlarged and tapered portions of hole 43 extend approximately half the depth of such hole thus leaving substantially one-half of the original hole for good bearing support. Hence, barrel 50 may be raised an appreciable amount above the horizontal to facilitate insertion of barrel 50 into barrel support 39. Yet when barrel 50 is lowered into its horizontal position as will be described in more detail later, the barrel will be amply supported

by the remaining cylindrical portion 46 and 47 of hole 43.

In the bottom of front spacer 5 there is provided a centrally located vertical threaded hole 48. A stop 49 (Fig. 2) comprising a cylindrical head portion 51 and a stem portion 52 is inserted in hole 48 with the head portion uppermost. A raised arcuate rib 53 is provided on the end of head portion 51 which engages a shoulder 54 formed by a reduced diameter section of a hydraulic cylinder 55 which extends forwardly within tube 38. A spring 56 surrounds stem portion 52 of stop 49 and is retained thereon by a gland 57 screwed into the bottom of hole 48. A lever 58 is pivotally mounted on the lower end of stem portion 52 of stop 49 by a pin 59, the forward end of lever 58 being bifurcated to permit such mounting. Lever 58 normally rests against gland 57. A pin 60 projecting radially from the cylindrical head portion 51 of stop 49 engages a vertical slot 61 provided in the rear wall of hole 48 to prevent rotation of stop 49. Thus lever 58 is maintained in the position shown in Fig. 2.

A carrier actuating rod 62 projects out of the rear end of hydraulic cylinder 55 and is connected to a carrier slide 63 (Fig. 48) as by threads 64. The carrier slide 63 essentially comprises a long narrow rectangular frame-like member and such slide rests on top of the integral ribs 36 of side plates 2 and 3. Carrier slide 63 is connected to a breech block carrier 125 to actuate such carrier in a manner to be later described.

A buffer mechanism 65 (Fig. 1) is contained within the hole 10 in rear spacer 4. Buffer mechanism 65 comprises mainly two telescoping tubes 66 and 67, the tube 66 being slidably contained within tube 67 and a spring 68 being contained within tube 66. Tube 67 has one end

69 of reduced diameter which projects forwardly through a reduced diameter forward end portion 70 of hole 10. The rear end of tube 67 is conically beveled as shown at 71. A conically shaped head 72 having a slope corresponding to that shown at 71 is provided on the rear end of tube 66. A buffer ring 73 having a substantially conically shaped cross section surrounds buffer tube 66 and rests between the conically shaped head 72 of such tube and the conical end 71 of tube

70 67. The spring 68 is retained within tube 66 by cap 12 which is screwed onto threads 11 of rear spacer 4. A stud 74 mounted in the center of buffer cap 12 snugly engages the interior of spring 68 to keep such spring in alignment with the axis of buffer mechanism 65. A boss 75 is integrally formed on cap 12 and projects outwardly at right angles to the axis of the firearm on which is detachably mounted a shoulder rest (not shown).

60 Breech block 140 comprises a substantially V-shaped member having a vertical arm 146 and an upwardly and rearwardly sloped arm 147. A cartridge feeding T-slot 141 is provided on the forward vertical face of arm 146 as shown in Figs. 1 and 47. On the back face of the rearwardly sloped arm 147 of breech block 140 there is provided a T-shaped rib 142 (Fig. 24) which slidably connects breech block 140 with the breech block carrier 125 as will be described later.

70 A plurality of integral outwardly projecting locking lugs 143 (Fig. 23) are provided on the sides of vertical arm 146 which engage corresponding lugs in barrel extension 150 as will be described. The rear edges of lugs 143 are sloped slightly as shown at 143a to facilitate engage-

ment of such lugs with the locking lugs in barrel extension 150. Near the bottom of breech block 140 there is provided a rearwardly opening, counterbored, horizontal hole 144 of suitable shape to receive a firing pin 145.

Firing pin 145 (Figs. 46 and 54) is provided with an integral head 148, the rear end surface of which is sloped as shown at 149 for a purpose to be described. A spring 151 surrounds the body portion of firing pin 145 and abuts head 148 and the bottom of the counterbored portion of hole 144 to bias firing pin 145 rearwardly, thus retracting the forward end of such firing pin from the face of cartridge feeding T-slot 141. A longitudinal slot (not shown) is provided in the head 148 of firing pin 145 which is engaged by a transverse pin provided in breech block 140 (not shown). A hole 153 is provided in breech block 140 as shown in Figs. 23 and 25 to receive such transverse pin. Such pin is provided to maintain the sloped end 149 of firing pin 145 in the position shown in Fig. 1. The firing pin 145 is retained within hole 144 of breech block 140 by a dovetail plate 166 which is inserted in a corresponding transverse dovetail slot 167 in the rear of breech block 140. A sloped rear corner 168 is provided on firing pin 145 which strikes against plate 166 thereby limiting the rearward travel of such firing pin.

A horizontal longitudinal hole 154 (Fig. 47) is provided near the top of vertical arm 146 of breech block 140 and a cartridge detent 155 is inserted therein. An integral head 156 is provided on the rear end of detent 155 while the forward upper end of detent 155 is suitably beveled as shown at 157 so that such detent will be cammed rearwardly to permit a cartridge to freely enter T-slot 141 when the breech block 140 is raised to the locked position.

Detent 155 is likewise provided with an arcuate surface 155a on the underside of the forward end of such detent which engages the rim of a cartridge. As will be described, during unlocking of the breech block 140, such block drops vertically until the arcuate surface 155a of detent 155 strikes the rim of the cartridge. Breech block 140 is abruptly arrested with the lugs 143 therein in alignment with the openings of barrel extension 150 to permit disengagement of breech block 140 from such barrel extension. This will be described in more detail later.

A slot 158 is provided on the underside of head 156 in which is inserted a flat spring 159 to bias detent 155 forwardly while at the same time holding such detent in proper alignment. A lever 510 is pivotally mounted on head 156 of detent 155 by a pin 511 as shown in Fig. 3. Such lever is bifurcated to surround head 156 and the function thereof will be later described.

A lower cartridge detent 160, similar to detent 155, is inserted in a hole 161 suitably spaced from hole 154 so that detents 155 and 160 will securely yet yieldingly hold a cartridge therebetween as will be further described. Lower cartridge detent 160 is likewise provided with an integral head 162. A shelf portion 163 produced by a flat milling cut is provided on the head 162 of detent 160 on which is placed the other end of spring 159 to bias the detent 160 forwardly into the cartridge feeding T-slot 141. Spring 159 is supported at its center section by a pin 164 inserted in a suitable hole 165 midway between detents 155 and 160 in the vertical arm 146 of breech block 140.

A third cartridge detent 169 is positioned

somewhat below the detent 160 to prevent the fired cartridge case from working back up the T-slot, and further to arrest the downward movement of the breech block 140 relative to the carrier 125 at an unlocked position relative to the barrel extension 150 when no cartridges are in the feedway, as will be later described. The cartridge detent 169 comprises a plunger having an integral head 170. The detent 169 is inserted within a horizontal hole 171 extending rearwardly from the face of T-slot 141. The forward portion of hole 171 is counterbored to accommodate the head 170 of detent 169. A helical spring 172 surrounds the detent 169 and is placed adjacent head 170. The spring 172 is likewise placed within the counterbored portion of hole 171 and thus biases detent 169 forwardly. Detent 169 is retained within hole 171 by a transverse pin 173 which engages a notch 174 in detent 169. The upper corner of head portion 170 of detent 169 is sloped as shown at 360 to permit a loaded cartridge case to readily slide downward over such detent. The lower edge of head 170 is formed at right angles to the axis of detent 169 to effectively stop the upward travel of an empty cartridge case in T-slot 141 as previously mentioned.

A breech block stop 176 is secured to the inclined arm 147 of breech block 140 near the top of such member as shown in Figs. 1, 7 and 44 by a screw 177. The stop 176 comprises a substantially rectangular member provided on the right side thereof with a downwardly projecting lug 178. An upwardly sloped surface 179 is provided on the lower forward corner of lug 178 to clear the breech block carrier 125 as will be described. A rear surface 180 of the downwardly projecting lug 178 engages an integral lug 135 on breech block carrier 125 as will be later described. An upwardly projecting lug 181 is provided on the other end of stop 176. The lower corner of the upstanding lug 181 is arranged to be engaged by a breech block depressor 200, to be described, to retain breech block 140 in the raised position shown in Fig. 1.

Near the top of sloped arm 147 of breech block 140 there is provided a hole 182 (Fig. 9) in which is inserted a detent 183. The detent 183 comprises a plunger having a stem portion 184. The detent 183 projects somewhat beyond the T-shaped rib 142 and is biased outwardly in such direction by a spring 185 which surrounds the stem portion 184 of detent 183. The hole 182 is counterbored to accommodate the spring 185 and the extreme end of such counterbored portion is threaded and a screw 186 is screwed therein to retain spring 185 within the hole 182. The detent 183 cooperates with a recess 183a on the carrier 125 to retain the breech block in an elevated position on the carrier while the barrel travels forwardly after unlocking, as will be later described in greater detail.

The breech block carrier 125 comprises a horizontal arm 126 and an integral upwardly inclined arm 127 as shown in Figs. 1 and 45. Integral projecting longitudinal guide ribs 128 are provided on each side of the horizontal arm 126 of breech block carrier 125 to slidably mount such carrier in the guideways 35 in the side plates 2 and 3. A transverse hole 129 is provided in the lower rear corner of carrier 125 as shown in Fig. 1 in which is inserted a pin 130 to connect the breech block carrier 125 with carrier slide 63 as will be later described.

On the forward face of the inclined arm 127 of carrier 125 (Figs. 1 and 54) there is provided

a T-slot 131. The T-shaped rib 142 on breech block 140 slidably engages T-slot 131 and thus the inclined forward face of arm 127 of carrier 125 functions as a guide for movement of the breech block relative to the carrier. Along the bottom of T-slot 131 in arm 127, a longitudinal rectangular recess 132 is provided to slidably mount a hammer 133. The hammer 133 is a substantially rectangular member provided with an integral lug 134 on the upper surface thereof as shown in Figs. 1 and 46. The lug 134 has a sloped, forwardly facing surface 136. When hammer 133 is placed within recess 132, the sloped surface 136 on lug 134 mates with sloped surface 149 on the end of firing pin 145. A rearwardly opening hole 137 provided in hammer 133 along the longitudinal axis thereof, houses a helical hammer spring 138. The spring 138 is retained within hole 137 by a headed rod-like member 187. The head portion of the member 187 rests on top of inclined arm 127 to seal the end of a hole 188 which communicates with the rectangular recess 132. The member 187 is retained within hole 188 by a pin 189 inserted in a transverse hole 190 near the top of the inclined arm 127 of carrier 125.

The lower end of hammer 133 is bifurcated as shown at 139 in Fig. 1. It should be mentioned here that hammer 133 is substantially shorter than the rectangular recess 132 to permit considerable longitudinal movement of hammer 133 within such recess in order that hammer 133 can obtain sufficient momentum to strike firing pin 145 a smart blow.

A horizontal longitudinally extending hole 191 is provided in the horizontal arm 126 of breech block carrier 125 to house a sear 192. The sear 192 is a substantially cylindrical member provided on the rear end with an integral tang 193 (Figs. 3 and 39) disposed at right angles to the axis of the cylindrical body of such sear. The tang 193 projects outwardly somewhat beyond the side of carrier 125 through a suitable horizontal slot in such carrier. Sear 192 is arranged to be biased forwardly by a spring 195. This spring 195 is contained within a rearwardly opening, hollow bore 196 to sear 192. The sear 192 and sear spring 195 are retained within the hole 191 by a plug 197 inserted in the rear end of hole 191. Plug 197 is retained in the position shown in Fig. 1 by a pin 198 inserted in a suitable vertical hole at the rear of arm 126. The forward end of sear 192 is provided with a notch 8 (Figs. 1 and 39) so that the end of hammer 133 can be engaged by such end and retained thereon until released, as will be described later.

The carrier slide 63 (Figs. 1 and 48) is a substantially rectangular integral member and is skeletonized so that such member comprises two comparatively long bars 71 joined at their forward end by a cross member 78 to which is connected the carrier actuating rod 62 as previously described. The two bars 71 are joined at their rear end by a cross member 79. In the center of the cross member 79 there is provided an integral lug 80 which is substantially rectangular in configuration and enters a suitable recess 81 provided on the underside of carrier 125. Carrier slide 63 is connected to breech block carrier 125 by the horizontal transverse pin 130 as previously described.

The hammer 133 is cocked by a cocking member 82. The cocking member 82 is a substantially triangular member and is inserted in a

slot 84 provided on the underside of carrier 125. The cocking member 82 is pivotally mounted within a slot 84 on a transverse pin 83. The transverse pin 83, however, is of rectangular configuration where such pin passes through cocking member 82. A rectangular hole 85 is of course provided in cocking member 82 to accommodate such rectangular portion on pin 83. One of the apexes 86 of cocking member 82 passes between the bifurcated end 139 of hammer 133 to force hammer 133 upwardly when the lower apex 87 of cocking member 82 strikes the sloped surface 27 on the upstanding lug 26 provided on bottom plate 6 as carrier 125 moves rearwardly.

There is pivotally secured to the left end of pin 83, as shown in Fig. 10, a firing pin retracting lever 88. Lever 88 is secured to pin 83 in such fashion as to permit limited pivotal movement of such lever about pin 83. An integral lug 89 is provided on the end of pin 83 which rests within a substantially V-shaped recess 90 provided on the end of lever 88. A leaf spring 118 is secured within a suitable recess in the underside of cross member 79 of carrier slide 63. Leaf spring 118 extends forwardly and is provided with a rounded end 119 as shown in Fig. 1. Such rounded end contacts a projection 120 formed by notching the rear corner of cocking member 82. Spring 118 is provided to bias cocking member 82 upwardly and hence lever 88 downwardly into the path of a sloped end 104 of a reciprocable operating slide 175. The forward end of lever 88 is provided with a transversely outwardly projecting lug 91 to engage the rear end of operating slide 175.

The operating slide 175 (Figs. 1, 2 and 43) essentially comprises a rectangular bar. Near the rear end of such bar there are provided two horizontal, oppositely disposed, integral lugs 92 which engage the slides of T-slot 37 provided in the side plates 2. A bracket 93 having an integral downwardly projecting lug 94 is secured to the forward end of the operating slide 175 as by two rivets 95. Integral lugs 96 oppositely disposed to one another are provided on the edges of bracket 93 to likewise engage the inside edges of T-slot 37. The walls of T-slot 37 are cut away as shown at 97 to permit assembly of operating slide 175 to T-slot 37.

An operating slide actuator 98 is pivotally secured to the downwardly projecting lug 94 as by a pin 99. Actuator 98 comprises a rectangular bar which is preferably skeletonized as shown in Figs. 1 and 43, for lightening purposes. The rear end of actuator 98 is slidably retained within a bracket 16 underneath the receiver as shown in Fig. 5. A handle 102 comprising a short tubular member is secured to operating slide actuator 98 by a chain 103 to facilitate manual retraction of actuator 98 and operating slide 175 as will be later described. The rear end of operating slide 175 is provided with sloped surface 104 which cooperates with firing pin retracting lever 88 as previously mentioned. Sloped surface 104 terminates in a vertical shoulder 121 as shown in Fig. 43.

Operating slide 175 is provided to manually charge or load the firearm. Such slide likewise provides means for retracting the firing pin as will be presently described. This is quite necessary in the event a misfire should occur. As will be brought out later, if the action were retracted without retraction of the firing pin, the breech block 140 would slide down the breech block car-

rier 125 and thus break the tip of the firing pin.

When operating slide 175 is retracted rearwardly by means of handle 102, the sloped end 104 of operating slide 175 strikes the lower corner of lug 91 of firing pin retracting lever 88. Upon striking the end of such lug, cocking member 82 is forced upwardly a slight amount which likewise forces hammer 133 upwardly. This upward movement of hammer 133 lifts lug 134 from the head 148 of firing pin 145. Firing pin 145 is then retracted by the bias of spring 151 until the sloped corner 168 provided on the underside of head 148 strikes the plate 166. The forward end of firing pin 145 will then be sufficiently retracted from the face of breech block 140 so that there will be no interference with the cartridge in the T-slot 141 of breech block 140. As the sloped surface 104 on the end of operating slide 175 strikes lug 91, lever 88 is raised upwardly along such sloped surface until the extreme rear end of lug 91 strikes shoulder 121 provided on operating slide 175. Upon striking shoulder 121, the lever 88 is prevented from rotating further and hence carrier slide 63, carrier 125 and breech block 140 will be moved rearwardly by operating slide 175.

As the recoil stroke is completed, cocking member 82 rides up cam surface 27 of lug 26 and hammer 133 is raised upwardly sufficiently to permit sear 192 under the bias of spring 195 to slide under the bottom end of hammer 133 thus retaining hammer 133 in the cocked position.

The carrier latch 100 (Figs. 1 and 3), as previously mentioned, is pivotally mounted between lugs 28 on rear bottom plate 6. On the rear end of carrier latch 100, on the upper surface thereof, there is provided an upright bifurcated integral lug 105. Rear corner 106 of lug 105 is suitably shaped to engage a shoulder 107 provided on the underside of carrier 125 for the purpose of retaining carrier 125 in the extreme rear or recoiled position as will be later described. Carrier latch 100 is pivotally mounted between lugs 28 on bottom plate 6 by a transverse pin 109 supported in suitable holes 29 in the lugs 28. A spring 117 is provided to bias latch 100 upwardly into the path of carrier 125. One end of spring 117 is placed underneath the rear end of latch 100 within a suitable recess while the other end of spring 117 rests in a suitable recess in the top of rear bottom plate 6.

A carrier latch release member 110 is pivotally secured to the forward edge of carrier latch 100 by a transverse pin 111. The latch release 110 is bifurcated to permit such member to surround lug 26 on bottom plate 6. The latch release 110 slopes downwardly and forwardly as shown in Figs. 1 and 3 and terminates in a toe portion 112. A recess 112a is provided in bottom plate 7 to receive toe portion 112 when such toe portion is forced downwardly as will be presently described. The release 110 rests on the top of the downwardly sloped portion 25 of bottom plate 6 as shown at 113. The point of contact at 113 acts as a fulcrum so that when breech block 140 slides down on breech block carrier 125 and strikes the toe 112, carrier latch release 110 will be depressed thereby releasing carrier 125. Immediately forward of the toe 112, a recess 114 is provided in forward bottom plate 7 in which is placed an insert 115 preferably of hard fibrous material to cushion the impact of breech block 140 as the breech block drops downwardly as will be later described. The insert 115 is secured to bottom plate 7 by a screw 116.

A breech block depressor 200 is pivotally mounted on the left side of breech block carrier 125 as shown in Figs. 5, 7, 8, 9, and 10. The breech block is arranged to be disengaged from breech block carrier 125 by the breech block depressor 200 at the desired time, as will be later described. The depressor 200 comprises a body portion 122 having in the center thereof an integral upright arm 123. The extreme upper portion of arm 123 is bent forwardly somewhat as shown in the above figures, and a notch 124 is provided in the uppermost corner thereof to engage lug 181 of stop 176.

Depressor 200 is fixedly secured to the left hand end of a transverse pin 199. Pin 199 is journaled within a transverse hole 201 in breech block carrier 125. A latch 202 is fixedly secured to the right hand end of pin 199 and adjacent the outside of carrier 125 as shown in Fig. 3. The bottom surface of the body portion 122 of depressor 200 rests on the top surface of the horizontal arm 126 of carrier 125. The forward edge of body portion 122 is rounded as at 203 to permit rotation of depressor 200 about the axis of pin 199. A plunger 204 suitably spring biased is vertically mounted within a suitable downwardly opening hole in the rear edge of body member 122 to bias the arm 123 in a counterclockwise direction to insure that notch 124 will engage the lower corner of lug 181 of stop 176. A roller 205 is mounted on a fixed stud 205a on the side of body portion 122.

A depressor bar 207 (Figs. 5, 7, 8, 9, 10) comprises a substantially rectangular bar slidably mounted on the left side of the gun for reciprocating longitudinal movement. On the forward end of depressor bar 207 there are provided two transversely projecting, integral lugs 208 (Fig. 3). A latch 209 is pivotally mounted between the lugs 208 on a suitable pin which is supported by lugs 208. Latch 209 is biased inwardly against barrel extension 150 by a suitable spring (not shown). The latch 209 engages a stud 211 (Figs. 5, 8, 10) provided on the side of barrel extension 150 to carry depressor 207 forwardly as will be presently described.

On top of depressor bar 207 an overhanging rib 212 (Fig. 1) is provided which engages the top surface of side plate 2 to provide bearing support for bar 207. An upwardly sloped cam surface 206 is formed on a vertical lug 213 provided on the rear end of rib 212. Lug 213 also projects inwardly as shown in Fig. 3 so as to engage roller 205 on depressor 200. An overhanging shelf 214 is secured to an integral raised lug 215 on depressor bar 200 by two rivets 216. The lug 215 is preferably slotted and the shelf 214 is inserted in such slot prior to riveting. The overhanging shelf 214 projects over the forward end of cam surface 206 and is provided to engage roller 205 to disengage depressor 200 from lug 181 thus permitting breech block 140 to become disengaged from barrel extension 150. Two longitudinal slots 217 and 218 are provided at the rear and forward ends of depressor bar 207 through each of which is inserted a screw 219. A washer 220 is placed under the head of each screw 219 which bears against the side of depressor bar 207 to provide increased bearing support. Screws 219 are screwed into suitably threaded holes in side plate 2 and are so tightened as to permit free longitudinal movement of depressor bar 207 within the limits of slots 217 and 218 on side plate 2.

The barrel extension 150 (Figs. 1 and 49) comprises a substantially rectangular block. A ver-

tical T-slot 221 (Fig. 49) is provided in the rear portion of barrel extension 150. A threaded hole 222 communicates between the front face of barrel extension 150 and the back of T-slot 221. The breach end of barrel 50 is screwed into threaded hole 222 as shown in Fig. 1. Two parallel integral ribs 223 are provided on the bottom surface of barrel extension 150 which engage the guideways 35 provided in each side plate 2 and 3. A plurality of integral locking lugs 224 are provided on each side of T-slot 221 which are engaged by the locking lugs on breech block 140. The front edges of lugs 224 are sloped forwardly from the bottom to the top in order to permit ready entry of breech block lugs 143 into T-slot 221 and yet permit snug engagement with rear edges 143a when the upward movement of breech block 140 is completed. A cartridge support 225 is centrally secured to the top of barrel extension 150 by a screw 226 as shown in Fig. 1.

A threaded sleeve 227 is screwed onto the barrel as shown in Fig. 2. Sleeve 227 has an integral downwardly projecting lug 228 which engages an annular groove 229 provided on the head of a piston rod 230 which projects out of tube 38.

A feedway 231 is transversely mounted on top of side plates 2 and 3 and substantially comprises a horizontal shelf 232 (Figs. 20 and 29). A large rectangular depending portion 233 is provided on the underside of shelf portion 232 which is bifurcated by a semi-circular cut 235 to permit the feedway 231 to be lowered over barrel 50 as will be presently described. A rectangular recess 234 is provided in the rear depending portion of 233 (Fig. 29) to permit the barrel extension 150 to slide forwardly underneath shelf 232 a short distance. Two oppositely disposed lugs 246 are formed by the semi-circular cut 235 each of which is bifurcated as shown at 247 (Fig. 22) and a longitudinal hole 248 is provided in each of the lugs 246. A broad T-slot 236 (Figs. 21 and 22) parallel to the longitudinal sides of shelf portion 232 is provided on the top of such shelf portion to receive a cartridge strip 237 to be presently described. A raised rib 238 is centrally provided on the bottom of T-slot 236 for a purpose to be described. An integral substantially cylindrical housing 239 is provided on the left side of feedway 231 as shown in Figs. 20 and 29. The cylindrical housing 239 contains a spring tape 240 for actuating the cartridge strip 237.

Feedway 231 is pivotally mounted on the right side of the firearm by a bracket 241 (Fig. 50). The bracket 241 is placed within a suitable vertical slot (not shown) on side plate 3 and is secured thereto preferably by suitable screws. An integral lug 244 is provided on top of bracket 241 and a longitudinal hole 245 is provided in such lug. The right-hand lugs 246 of the feedway are placed over lug 244 of the bracket 241 and a pin 249 is inserted through hole 248 and hole 245 in bracket 241. Pin 249 is suitably secured within the hole 248 to prevent accidental displacement thereof. Thus the pin 249 pivotally mounts feedway 231 to the right hand side plate 3.

On side plate 2 opposite bracket 241 there is mounted a bracket 250 as shown in Fig. 5. Bracket 250 is placed within a suitable vertical slot (not shown) in side plate 2 and bracket 250 is secured to such side plate by screws 252. An upwardly projecting lug 253 is provided on the upper edge of bracket 250 and a longitudinal slot 255 (Fig. 17) communicates with hole 254 to permit a feedway

release pin 256 to enter therein as will be presently described.

When feedway 231 is rotated into position over barrel 50, the bifurcated left-hand lug 246 of the feedway engages lug 253 on bracket 250 thereby aligning holes 254 and 248 as shown in Fig. 5. Feedway release pin 256 comprises a pin 257 having an integral head 258. A flat milled section 259 is provided in the center of pin 257 of slightly lesser width than slot 255 on lug 253 of bracket 250. Thus pin 256 enters hole 254 through slot 255. When pin 256 is rotated counterclockwise feedway 231 is locked to bracket 250. A suitable recess 260 is provided on the top of the rear edge of shelf portion 232 to accommodate the cartridge support 225 and to provide clearance for breech block 140.

A longitudinal hole 261 (Figs. 20 and 22) is provided in the portion 233 underneath shelf portion 232 in which is inserted a cartridge strip retaining plunger 262. The plunger 262 comprises a hollow tubular member having an integral upwardly extending head 263 at the forward end thereof. Head 263 rests within a suitable recess 264 in the left-hand edge of T-slot 236. A helical spring 265 is placed within the hollow interior of plunger 262 and is retained therein by a cylindrical member 266. Such member is in turn retained by a pin 267 inserted in a vertical hole 268 in the bottom of T-slot 236 and in turn passes through a slotted hole 269 in plunger 262 thence through a suitable hole in cylindrical member 266. Limited longitudinal movement of plunger 262 is thus provided by the slotted hole 269. Spring 265 biases the headless end of plunger 262 into the rectangular recess 234 and head 263 into the path of the cartridge strip 237 as will be described. The end of plunger 262 projecting into recess 234 is struck by the forward face of barrel extension 150 for the purpose of pushing head 263 of plunger 262 out of the path of strip 237 to permit feeding another round into the action of the firearm as will be later described.

The cartridge strip actuating tape 240 is wound about a spool 271 which is inserted within cylindrical housing 239. The spool 271 is provided with an integral flange 272 to retain tape 240 on such spool as shown in Fig. 21. A spindle 273 is provided for mounting spool 271. Such spindle has an integral head 274 which is rotatably supported by the rear wall of cylindrical housing 239. Adjacent spool 271 a squared portion 275 is provided on spindle 273 and upon such squared portion a hub 276 is placed. A spring retainer 277 of the same diameter as spool 271 is inserted within housing 239 and likewise placed adjacent spool 271. Two integral outwardly facing oppositely disposed lugs 278 are provided on retainer 277. One end of a flat clock-type spring 279 is secured to hub 276 in suitable fashion while the other end of spring 279 is secured to retainer 277 by means of a rivet 280. Spring 279 is arranged to be wound by a disk-like cover 281. An integral knob 282 having a knurled outer surface is centrally provided on the cover 281 to facilitate turning such cover and winding spring 279 as will be presently described.

An axial cylindrical recess 283 is provided on the rear end of cover 281 to support the forward end of spindle 273. Two oppositely disposed arcuate slots 290 are provided on the underside of cover 281 which are engaged by the lugs 278. One end of tape 240 is secured to spool 271 by passing that end of such tape about a pin 270 and inserting the tape and such pin in a transverse slotted

hole 284 in spool 271 as shown in Fig. 20. The tape 240 is then wound about spool 271. The other end of tape 240 is passed along the bottom of a longitudinal T-slot 285 provided in rib 238 of feedway 231 where it connects with a strip actuating slide 286. Slide 286 comprises a base 287 conforming in shape to the T-slot 285 and an integral lug 288 provided on the top of such base. The right hand end of base 287 is rounded as shown in Fig. 20 and the end of tape 240 passes around such rounded end and is secured to such slide in the same manner as to spool 271. A slot 289 is provided on the underside of lug 288 as shown in Fig. 20 which engages the end of cartridge strip 137 as will be presently described.

The cover 281 is restrained against turning by a locking spring 291 (Figs. 3, 5, 21 and 53) which comprises a rod-like member having one end of reduced thickness. On the underside of such spring there is provided an integral projection 292 which engages a slot 293 on the top surface of knob 282. The rod-like portion of spring 291 is inserted in a hole 294 in feedway 231 as shown in Fig. 5. The projecting end of spring 291 is turned upwardly for convenience in grasping as shown in Fig. 53. To place clock-type spring 279 under tension, spring 291 is raised to disengage projection 292 from slot 293. Knob 282 may then be turned in a counterclockwise direction as shown in Fig. 21 until spring 279 is under the tension desired. When spring 279 is placed under tension, such force is transmitted to spool 271 and in turn to tape 240 for actuating cartridge strip 237 as will be presently described.

The cartridge strip or cartridge feed member 237 comprises a shallow, channel shaped member having outwardly flared sides 295 which rest within T-slot 236 as shown in Fig. 21. A plurality of cartridge clips 296 comprising substantially semi-cylindrical tubes are secured to the top surface of strip 237 as by rivets 297. The clips 296 are tapered as shown in Figs. 3 and 19 to conform to the taper of a cartridge case 300. The sides of clips 296 engage somewhat more than half the periphery of each cartridge 300 as shown most clearly in Fig. 21 to securely, yet yieldingly, hold such cartridge case. An integral spring positioning detent 298 is provided on the rear end of each clip which is suitably formed to fit within an extractor groove 299 provided at the rear end of each cartridge 300 and strike the inside of the rim of each case 300 to align the bases of the cartridges in strip 237.

A plurality of wedge-shaped notches 301 (Fig. 19) are provided on the forward edge of each strip 237. The notches 301 have the same spacing as cartridge clips 296 and are provided to be engaged by the head 263 of cartridge strip retaining plunger 262. The cartridge strip 237 is inserted into the feedway from the left side of the firearm as shown in Fig. 3, the flared sides 295 engaging T-slot 236. The right end of cartridge strip 237 then engages slot 289 on the underside of lug 288 of slide 286 thereby unreeling tape 240 from spool 271. Thus tape 240 biases strip 237 to the left to bring each cartridge 300 into feeding position. A cartridge stop pawl 302 is pivotally mounted in the upper left-hand corner of feedway 231 as shown in Figs. 3, 19 and 51 to arrest and to align each cartridge in the feedway. Such pawl is pivotally mounted on a pin 303. A spring 304 is inserted within a suitable slot to bias one end 305 of

75 pawl 302 upwardly into the path of a cartridge 300.

5 A wedge-shaped sear release member 306 (Fig. 34), which has a T-shaped base 321, and a trigger 307 are mounted on a bracket 308 on the right side of the firearm as shown in Figs. 3 and 17. The bracket 308 is suitably secured to side plate 3 slightly ahead of sear tang 193 as shown in Fig. 3. A grip 309 is vertically mounted 10 in bracket 308 as by a bolt 310. The trigger 307 substantially comprises an L-shaped member as shown in Fig. 35 and is pivotally mounted on bracket 308 by a vertical pin 311. The forwardly projecting leg of trigger 307 is provided 15 with an elongated hole 312 which is engaged by a vertical pin 313 in a sear release housing 314 as shown in Figs. 36 and 37. Pin 313 also passes through wedge shaped sear release member 306 thereby pivotally securing such member to housing 314.

20 Housing 314 is a substantially rectangular member and is mounted in a T-shaped slot 315 provided on top of bracket 308. A transverse slot 316 is provided on the left hand side of housing 314 to receive a sear release plunger 317. Sear release plunger 317 is a T-shaped member provided with a cylindrical stem portion 318 (Fig. 38). A spring 319 surrounds the end of stem portion 318 to bias plunger 317 outwardly. 25 30 A spring-biased plunger 320 (Fig. 3) is inserted within a suitable hole in bracket 308 and engages the front surface of trigger 307 in such fashion that trigger 307 will be biased in a clockwise direction about pin 311.

35 The trigger mechanism illustrated in the appended drawings is utilized for semi-automatic fire. When the action is in the breeched or closed position shown in Fig. 3, sear 192 is released by pressing against trigger 307. Sear release member 306 which is pivotally secured to housing 314 is forced transversely across a tapered transverse slot 500 on the top edge of side plate 3. The wedge-shaped nose of sear release member 306 then wedges between sear tang 193 and breech block carrier 125 urging sear 192 rearwardly thereby effecting release of firing pin 145. The rearward movement of carrier 125 then rotates release member 306 rearwardly against the rear surface of tapered slot 500 whereupon such carrier and in fact the whole breech mechanism slides past such release member.

40 When the barrel extension has recoiled past the sear release member 306, plunger 317 biases such member outwardly into the path of barrel extension 150. It should be mentioned here that the T-shaped head of plunger 317 contacts some portion of base 321 of release member 306 at all times. Thus regardless of what position the release member 306 may assume, such plunger will force member 306 to the position shown in Fig. 3 when the trigger is released as will be presently described. As the barrel extension 150 moves forwardly on the counter-recoil stroke, such extension strikes sear release member 306 rotating such release member forwardly until it strikes the forward sloped surface of tapered slot 500, whereupon the breech mechanism will slide freely past sear release member 306. As the sear release member 306 has been thrust to one side, as just described, the weapon cannot be fired automatically, the sear release member having been disconnected from the sear 192. To again fire the weapon the trigger 307 is pushed forwardly whereupon housing 314 is forced away from the gun through the connection of such

housing to trigger 307 by the bias of plunger 320. Sear release member 306 is then returned to the position shown in Fig. 3 ready to effect release of sear 192 when trigger 307 is again actuated. It should be understood that such mechanism can be readily modified to permit automatic fire if desired.

A safety 323 comprising a knob portion 326 and a cylindrical stem portion 324 is mounted underneath housing 314 as shown in Figs. 3, 17, 36 and 37 so that the stem portion thereof can engage housing 314 in such fashion as to block the forward movement of such housing. A flattened portion 325 is provided in the center of stem portion 324. In the position shown in Fig. 37, safety 323 is in the inoperative position. When such safety is rotated in a counterclockwise direction as shown in Fig. 17, the flattened portion 325 is rotated into a transverse notch 314' provided on the bottom of housing 314 thereby effectively blocking any movement of such housing. Safety 323 is retained on bracket 308 by a spring clip 326a which surrounds a projecting end 327 of stem portion 324. Such spring clip likewise allows slight lateral movement of safety 323 which therefore permits use of a suitable detent (not shown) to yieldingly secure safety 323 in either the "safe" or "fire" position.

An action retaining stop 501 is mounted on the outside of side plate 3 somewhat to the rear of trigger bracket 308 as shown in Figs. 3 and 33. Such stop comprises a plunger 502 secured by a pin 503 to a knob 504. Knob 504 is slidably contained within a counterbored hole 505 in a gland 506. Gland 506 is horizontally mounted in a transverse threaded hole 507 in side plate 3. A spring 508 placed in the bottom of counterbored hole 505 biases knob 504 and plunger 502 outwardly. However, plunger 502 is prevented from being forced out of gland 506 by an integral collar 509 which surrounds the forward end of such plunger and strikes the gland 506. The other end of plunger 502 is conically shaped and engages a correspondingly shaped recess on the surface of the right end way of carrier 125.

To hold the breech block 140 and carrier 125 in the retracted position, such members are retracted by operating slide 175 until carrier 125 is slightly beyond stop 501. Knob 504 is then pushed and held inwardly until the conical end of plunger 502 is in the path of carrier 125. Carrier 125 is then let down slowly until the end of plunger 502 engages a suitable mating recess in carrier 125 whereupon block 140 and carrier 125 is held in the open position. To release stop 501, carrier 125 is moved rearwardly slightly and the bias of spring 508 forces plunger 502 out of the path of carrier 125.

The sight preferably used with this firearm is a telescopic sight 338 as shown in Figs. 5, 17, and 27 and is mounted on a bracket 328. Bracket 328 is pivotally mounted on side plate 2 by a screw 329 placed near the lower forward edge of bracket 328 as shown in Fig. 5. Rearwardly disposed to screw 329 there is provided an elongated hole 330 in bracket 328. An elevating knob 331 having a short cylindrical projection 332 on the underside thereof is provided for moving bracket 328 in an upwardly or downwardly direction. The projection 332 is eccentric with respect to the axis of knob 331 and snugly fits the sides of elongated hole 330. Knob 331 is provided with a knurled periphery to facilitate turning. Knob 331 is secured to side plate 2 by a screw 333 passing through an axial hole in such knob.

To adjust bracket 328 for elevation, the screws 329 and 333 are loosened slightly and knob 331 is rotated until the sight is raised or lowered for the elevation desired. Such elevation adjustment may be indicated by suitable graduations (not shown) on bracket 328 and by a suitable indexing mark on knob 331 (not shown). When knob 331 is rotated, bracket 328 is raised or lowered depending on the direction of rotation because of the eccentricity of projection 332 relative to screw 333. When proper adjustment is obtained, screws 329 and 333 are tightened to secure such adjustment.

Windage adjustment is readily obtained by providing a movable sight base 334 on top of bracket 328. The movable base 334 is pivotally secured to bracket 328 by a screw 335 placed at the forward end of base 334. A windage knob 336 is oppositely disposed to screw 335 and is secured to movable sight base 334 by a screw 337. The structural mounting of knob 336 is similar to that of knob 331 for providing windage adjustment. The telescope sight 338 is suitably secured to movable sight base 334.

A breech block guide 339 comprising a substantially rectangular bar is secured to side plate 3 slightly above the bottom plate as shown in Fig. 15. The rear corner of guide 339 is sloped somewhat as shown at 340 to more readily engage the breech block 140 as will be presently described. Immediately forward of guide 339 a breech block ramp 341 is secured to side plate 3 as by screws 342. Breech block ramp 341 comprises a bracket 343 of substantially rectangular configuration having an inwardly projecting lug 344 which is adjacent the forward end of forward bottom plate 7. An upwardly sloped ramp surface 345 is provided on lug 344 as shown in Fig. 15. When breech block 140 starts its forward travel, the rear end of breech block guide 339 enters the slot between the two lower locking lugs on the side of breech block 140 adjacent side plate 3 and the sloped surface 345 of breech block guide 339 facilitates such engagement. When breech block 140 strikes lug 344 of ramp 341, the ramp surface 345 eases the transition of breech block 140 from a horizontal movement to a vertical movement.

Operation

The cycle of operation of the firearm above described is as follows: Depress depressor latch 202 which disengages depressor 200 from lug 181 and withdraw the action, which essentially comprises breech block 140 and breech block carrier 125, by pulling operating handle 102 rearwardly. The action retaining stop 501 is pushed inwardly and the action is then allowed to go forwardly until breech block carrier 125 contacts such stop thereby engaging such carrier and holding the action in a partially open position. A loaded cartridge strip 237 is then inserted into the left end of feedway 231 as shown in Fig. 3. The front end of strip 237 engages slide 286 which is connected to tape 240. The strip is then pushed into the feedway until cartridge stop pawl 302 engages the last round, thereby retaining the cartridge strip 237 against the bias of tape 240. The action is then permitted to close by withdrawing such action slightly to the rear by pulling handle 102 rearwardly a short distance thereby automatically disengaging the action stop 501. When the breech block 140 rises vertically to the closed position, T-slot 141 engages the rim of the first cartridge 300 in strip 237.

To feed cartridge 300 now held in T-slot 141 of breech block 140 depressor 200 is disengaged from

lug 181 by depressing latch 202 as previously described so that breech block 140 can drop downwardly sufficiently to unlock from barrel extension 150. The action is then withdrawn rearwardly until the rear end of carrier 125 is approximately $\frac{1}{8}$ inch from buffer 65. When however the action is approximately two inches from the buffer 65 roller 205 on depressor 200 engages cam surface 206 on depressor bar 207. Depressor 200 then starts breech block 140 downwardly on carrier 125. When roller 205 strikes the vertical portion of cam 206 depressor 200 has fully depressed breech block 140 so that the cartridge 300 held within T-slot 141 is aligned with the chamber of barrel 50.

While the gun is being manually charged, depressor bar 207 is held stationary in the forward position through the connection of such bar to barrel extension 150 by a stud 211. During the last inch of rearward travel of the action, cocking member 82 strikes cam surface 27 of lug 26 thereby raising hammer 133 and cocking the firing mechanism as previously described. The handle 102 is then released and the driving spring (not shown) operating on rod 62 biases the action forwardly. As the breech block 140 starts forwardly, the lower locking lug of such breech block adjacent side plate 3, slides under sloped ramp surface 349 on breech block guide 339. Cartridge detents 155 and 160 vertically align cartridge 300 in T-slot 141. Thus the breech block 140 travels forwardly and holds such cartridge in alignment with the bore of barrel 50 until the cartridge 300 is thrust into the chamber of barrel 50. Thus the breech block 140 is held down until such breech block comes forward to strike ramp surface 345 whereupon the horizontal movement of breech block 140 is changed to a vertical movement. At this point the head of cartridge 300 forces detent 160 rearwardly, so that breech block 140 can rise vertically to the locked position. T-slot 141 then engages the head of another cartridge 300 as such second cartridge 300 strikes the beveled portion 157 of detent 155 and cams such detent rearwardly to permit such cartridge to enter T-slot 141.

It is desired to point out here that due to the recoil and counter-recoil mechanism described in my U. S. Patent No. 2,364,103, when retracting the action, force need be exerted only against the bias of the breech block operating spring (not shown) and not against the barrel recoil spring (not shown). Thus it is not necessary to move the comparatively great mass of barrel 50, nor does the barrel operating spring of considerable weight have to be compressed in order to manually charge the firearm.

The firearm is now charged and is ready to fire semi-automatically. Trigger 307 is then pushed forwardly which causes sear release member 306 to cam sear 192 rearwardly thereby releasing such a sear and thus effecting discharge of the cartridge as will be presently described. The barrel 50, the barrel extension 150, the breech block 140, and breech block carrier 125 now recoil as a unit until the breech block carrier strikes the buffer mechanism 65 at the rear of the firearm.

As barrel 50 and barrel extension 150 recoil rearwardly, the cartridge strip retaining plunger 262 is biased rearwardly by spring 265. The head of such plunger engages one of the notches 301 on strip 237 to secure such strip against lateral movement for a purpose that will be described later.

As shown in Fig. 10, the second round from

strip 237 still is held in T-slot 141. During the rearward travel of these components, cocking member 82 strikes cam surface 27 on lug 26 thereby pivoting cocking member 82 in a counterclockwise direction as viewed in Fig. 1, which raises hammer 133 upwardly whereupon the end of such hammer is engaged by the forward end of sear 192. Sear spring 195 biases sear 192 forwardly to effect such engagement. Firing pin 145 is, of course, retracted by the firing pin spring 151. The hydraulic cylinder 55, previously mentioned, absorbs a considerable amount of the recoil energy and helps reduce the shock against the buffer mechanism 65.

As the action approaches the end of the recoil stroke, roller 205 on depressor 200 passes under shelf 214 of lug 215 on depressor bar 207. This causes depressor 200 to become disengaged from lug 181 on breech block 140. Stud 211 on barrel extension 150 strikes the forward face of lug 215 to carry depressor bar 207 to the rear. Such bar is forced rearwardly to prevent roller 205 from binding on cam surface 206.

At the end of the recoil stroke, the remaining recoil energy of the recoiling members is absorbed by the buffer mechanism 65. When the rear end of carrier 125 strikes the forward end 69 of tube 67, the conically beveled portion 71 of such tube expands conical buffer ring 73 outwardly to bear against the wall of hole 10. A portion of the force striking tube 67 is transmitted through ring 73 to the conically shaped head 72 of buffer tube 66. This forces tube 66 to slide rearwardly compressing spring 68. Thus it is apparent that the recoil force striking the reduced diameter end portion 69 of tube 67 is largely transmitted to the wall of hole 10 through friction of ring 73. A portion of the recoil force is of course absorbed by spring 68. After the action starts its counterclockwise stroke, ring 73 is no longer under compression hence tubes 66 and 67 slide forwardly under the bias of spring 68 to be in operative position.

The bias of the barrel recoil spring and driving spring (not shown) then start the recoiling members forwardly on the counter-recoil stroke. Carrier latch 109 engages shoulder 107 on carrier 125 thereby detaining such carrier. Barrel extension 150 and barrel 50 however continue forwardly forcing breech block 140 to slide downwardly on the inclined arm 127 of carrier 125 until arcuate surface 155a of detent 155 strikes the rim of cartridge 300 resting on support 225 which is secured to barrel extension 150. This downward movement of block 140 aligns locking lugs 143 on such block with the openings between corresponding locking lugs on barrel extension 150. Thus barrel 50 and barrel extension 150 become unlocked from breech block 140 and move forwardly towards battery position by the bias of the barrel spring (not shown). Breech block 140 is yieldingly retained in the unlocked position on carrier 125 not only by the engagement between cartridge 300 and detent 155, but also by detent 183 in the breech block engaging recess 183a in the carrier until stud 211 on barrel extension 150 strikes latch 209 on depressor bar 207. The depressor bar is then carried forward by the barrel until the barrel comes to a final stop at its forward position as shown in Fig. 10. As the depressor bar 207 moves forwardly, shelf 214 moves off roller 205 and the cam surface 206 provided in the rear end of depressor bar 207 engages roller 205 and partially rotates depressor 200 in a counterclockwise direction as viewed in Fig. 10. This forces breech block 140 down the inclined sur-

face of carrier 125 thereby aligning the live cartridge 300 held in the T-slot by the cartridge detents 155 and 160 with the axis of the bore. The empty cartridge case extracted from the chamber of barrel 50 by the T-slot 141 is still held within the T-slot 141 and is prevented from moving upwardly by the lowest detent 160.

When breech block 140 is near the bottom of its travel downwardly on carrier 125, it strikes the upturned toe portion 112 of carrier latch release member 110. This disengages the rear corner 106 of carrier latch 100 from shoulder 107 thereby releasing carrier 125 from latch 100, permitting such carrier and breech block 140 to go forwardly to the closed position. Just prior to the barrel reaching the fully closed position, the barrel extension 150 strikes cartridge strip retaining plunger 262 as shown in Fig. 20 and forces the plunger out of engagement with notch 301 in strip 237 permitting strip 237 to move to the left as shown in Fig. 21 until the next round in strip 237 contacts cartridge stop pawl 302. This horizontally aligns the next cartridge in feedway 231 where it can again be engaged by T-slot 141 in breech block 140 as such breech block comes forwardly to the closed position shown in Fig. 1.

Upon release of the carrier 125 from carrier latch 100, the action moves forwardly until breech block 140 is engaged by breech block guide 339 as previously described. The guide 339 prevents breech block 140 from sliding back up the inclined surface of carrier 125 thereby preventing misalignment of cartridge 300 contained in T-slot 141 in breech block 140 with the chamber of barrel 50. When breech block 140 contacts ramp surface 345 of breech block ramp 341, breech block 140 is forced upwardly into locked relationship with barrel extension 150. The breech block is assisted in this upward movement by the carrier 125 which is moving forwardly and therefore raises breech block 140 upwardly on the inclined surface of carrier 125. As the breech block 140 moves vertically upwardly to the closed position, the fired case still retained in T-slot 141 is forced downwardly out of the bottom of barrel extension 150 while breech block 140 moves vertically upwardly whereupon it is ejected through the open bottom of the receiver 1. Cartridge strip 237 is not permitted to advance immediately the cartridge 300 is withdrawn from such strip, as otherwise a live cartridge would be immediately aligned with the one just extracted from such strip. In the event of a short recoil, if such was permitted, the action would close while still holding a live round in the T-slot 141 and the tip of the projectile could then strike the primer of a cartridge contained in strip 237 with dangerous consequences.

Upon extracting the last round from cartridge strip 237, slide 286 forcibly ejects the empty strip 237 clear of feedway 231 leaving such feedway 231 clear for quick insertion of a fully loaded strip. When the last round is fired, detent 169 contacts the rim of cartridge 300 contained within the chamber of barrel 50. At the end of the recoil movement of the last round, breech block 140 then drops down until bottom detent 169 strikes the base of cartridge 300 within the chamber of barrel 50. This aligns the locking lugs 143 of breech block 140 in such position that barrel extension 150 is readily unlocked from breech block 140 as the barrel goes forwardly on the counter-recoil stroke as previously described.

If it is desired to clear the feedway of the firearm, that is, remove a partially filled strip, the action is withdrawn to the rear sufficiently for the round just extracted from strip 237 to clear the feedway. Lever 510 is depressed which pulls detent 155 out of T-slot 141 and cartridge 300 contained therein can then be readily lifted out of the top of such slot. Strip 237 is then removed from feedway 231 by depressing pawl 302 which releases such strip. The action is allowed to go forward whereupon the cartridge extracted from the chamber of barrel 50 is ejected as previously described. Thus the weapon is readily cleared of live rounds.

Disassembly

To disassemble the barrel 50 from the firearm, breech block carrier 125 is moved rearwardly until it is retained by the action retaining stop 501. Feedway release pin 256 is rotated so that feedway 231 may be raised upwardly and pivoted about hinge pin 249. The barrel is then forced rearwardly until the forward face of barrel extension 150 clears the rear edge of feedway 231. The feedway can now be rotated upwardly out of the way of barrel 50 about pin 249. Latch 209 on the forward end of depressor bar 207 is then pivoted outwardly about a pin 210 at the same time lever 58, provided on the bottom side of front spacer 5, is pushed downwardly to disengage stem portion 52 from the shoulder 54. The barrel is then permitted to go forwardly. The hydraulic cylinder 55 then moves forwardly through front spacer 5. Barrel 50 is then raised upwardly at the breech end thereof, the ribs 223 provided on the bottom of the barrel extension 150 being disengaged from the guideways 35 through a suitable opening at the front end of such ways in side plate 2. The elliptically shaped hole 43 of front barrel bearing support 39 permits barrel 50 to be raised upwardly as previously mentioned. When the barrel has been raised as far as is possible, the barrel is withdrawn rearwardly from the front barrel bearing support. Thus the barrel is disassembled from the firearm. Assembly of such barrel is effected substantially by reversing the procedure for disassembly thereof.

Breech block 140 and breech block carrier 125 are readily disassembled from side plates 2 and 3 by unscrewing carrier rod 62 from slide 63. The breech block and breech block carrier are then moved rearwardly until pin 130, which secures breech block carrier 125 to slide 63, comes opposite a mating hole provided in side plate 2 (not shown). The pin 130 may then be readily driven out of hole 129 in carrier 125 through a corresponding mating hole in side plate 3. Thus carrier 125 is disconnected from slide 63. Carrier 125 and breech block 140 are then moved forwardly to the opening in the guideways 35 where such carrier and breech block may then be readily lifted out of the receiver. Carrier slide 63 may then be readily removed by simply lifting such carrier out of receiver 1.

Operating slide 175 is readily removed from side plate 2 by raising a spring biased stop 530 in side plate 2 (Fig. 6) and moving slide 175 forwardly until lugs 92 come opposite the enlarged portion 97 in the T-slot provided for such disassembly. The forward end of slide 175 is automatically disengaged from the forward end of T-slot 37. Operating slide 175 is then lifted out of slot 37 whereupon the rear end of operating slide actuator 98 falls out of bracket 16.

Assembly of these components is readily accom-

plished by reversing the procedure for disassembling. Disassembly and assembly of the remaining components is readily apparent to those skilled in the art and need not be further described.

I claim:

1. In a firearm having a receiver, a barrel extension slidably mounted in said receiver for reciprocating movement, a barrel secured to said barrel extension for movement therewith, a breech block carrier slidably mounted in said receiver for reciprocating movement parallel to said barrel movement, a breech block guide surface on said carrier angularly disposed relative to the path of movement of said carrier and located rearwardly of said barrel extension, a breech block slidably mounted relative to said guide surface for reciprocal movement between two spaced positions on said guide surface, and means for locking said breech block to said barrel extension in one of said spaced positions of said breech block, said breech block arranged to unlock from said barrel extension when in the other of said spaced positions on said carrier.

2. The combination defined in claim 1 wherein said locking means comprises a plurality of spaced projecting lugs on said barrel extension and a plurality of spaced, projecting lugs on said breech block, said lugs on said breech block being constructed and arranged to lie in alignment with said lugs on said barrel extension in said locking position of said breech block on said carrier and to align with the spaces between said lugs on said barrel extension in said other position of said breech block on said carrier.

3. In a firearm having a barrel extension, a barrel, and a longitudinally extending receiver, the improvement comprising a breech block carrier slidably mounted in said receiver for reciprocating longitudinal movement, a breech block guide surface on said carrier angularly disposed relative to the path of movement of said carrier and located rearwardly of said barrel, a breech block slidably mounted relative to said guide surface for reciprocal movement between two spaced positions on said guide surface, and means for locking said breech block to said barrel extension in one of said spaced positions of said breech block, said breech block arranged to unlock from said barrel extension when in the other of said spaced positions on said carrier.

4. The combination defined in claim 3 wherein said locking means comprises a plurality of spaced projecting lugs on said barrel extension and a plurality of spaced, projecting lugs on said breech block, said lugs on said breech block being constructed and arranged to lie in alignment with said lugs on said barrel extension in said locking position of said breech block on said carrier and to align with the spaces between said lugs on said barrel extension in said other position of said breech block on said carrier.

5. In a firearm having a receiver, a barrel extension slidably mounted in said receiver for movement between a battery and a recoil position, a barrel secured to said barrel extension, resilient means for opposing recoil movement of said barrel, a breech block carrier slidably mounted in said receiver for reciprocating movement parallel to said barrel and barrel extension movement, a breech block guide surface on said carrier angularly disposed relative to the path of movement of said carrier and located rearwardly of said barrel extension, a breech block slidably mounted relative to said guide surface

for reciprocal movement between two spaced positions on said guide surface, means for locking said breech block to said barrel extension in one of said spaced positions of said breech block, thereby locking said carrier to said barrel extension for recoil movement therewith, and a latch engageable with said carrier in its recoiled position whereby forward movement of said barrel under the bias of said resilient means moves said breech block to its said other position on said carrier.

6. The combination defined in claim 5 plus means responsive to said movement of said breech block on said carrier for releasing said latch from said carrier, and resilient means for biasing said carrier to its battery position.

7. In a firearm having a receiver, a barrel extension slidably mounted in the receiver for reciprocal longitudinal movement, a barrel secured to said barrel extension for movement therewith, a breech block carrier slidably mounted in the receiver rearwardly of said barrel extension for longitudinal movement between a recoiled and a battery position, a breech block guide surface on the front of said carrier, said surface being inclined relative to the path of movement of said carrier, a breech block slidably mounted on said guide surface for reciprocal movement between an upper and a lower position thereon, means for locking said breech block to said barrel extension during movement to and from said upper position on said carrier, said breech block and barrel extension arranged to unlock during movement toward said lower position, and means for camming said breech block from said lower position to said upper position as said carrier approaches battery position.

8. The combination defined in claim 7 wherein said last-mentioned means comprises a pair of upwardly inclined ramp surfaces disposed on opposite sides within the receiver and arranged to convert longitudinal movement of said breech block to vertical movement, said inclined guide surface on said carrier arranged to continue vertical movement of said breech block until the latter reaches said upper position.

9. In a firearm having a receiver, a barrel extension slidably mounted in the receiver for reciprocal longitudinal movement, a barrel secured to said barrel extension for movement therewith, said barrel extension having a vertical T-slot portion at the rear end thereof, a plurality of spaced inwardly projecting lugs vertically disposed on either side of said T-slot portion, a breech block carrier slidably mounted in the receiver rearwardly of said barrel extension for reciprocal longitudinal movement between a recoiled and counterrecoiled position, a breech block guide surface on the front of said carrier, said surface angularly disposed relative to the path of movement of said carrier, a breech block slidably mounted on said guide surface for reciprocal movement between an upper and lower position thereon, said breech block having a plurality of spaced outwardly projecting lugs vertically disposed on either side thereof and arranged to pass underneath said barrel extension lugs when said breech block lies in said lower position, and means for camming said breech block at the end of longitudinal counterrecoil movement thereof into said upper position whereby said breech block lugs engage behind said barrel extension lugs and lock said breech block to said barrel extension.

10. The combination defined in claim 9 wherein

the rear edge of said breech block lugs is inclined and the front edge of said barrel extension lugs is oppositely inclined to facilitate said locking movement of said breech block.

11. The combination defined in claim 9 plus means in the receiver for guiding said breech block during longitudinal counterrecoil movement so as to maintain said locking lugs thereon in a lower plane than said locking lugs on said barrel extension.

12. In a firearm having a receiver, a barrel extension slidably mounted in the receiver for reciprocal longitudinal movement, a barrel secured to said barrel extension for movement therewith, said barrel extension having a vertical T-slot portion at the rear end thereof, a plurality of spaced inwardly projecting lugs on either side of said T-slot portion, a breech block carrier slidably mounted in the receiver rearwardly of said barrel extension for reciprocal longitudinal movement, a breech block guide surface on the front of said carrier extending upwardly and rearwardly relative to the path of movement thereof, a V-shaped breech block having a first arm portion extending upwardly and vertically with respect to the path of movement of said carrier and a second arm portion inclined rearwardly relative to said first arm portion and arranged to slidably mate with said guide surface on said carrier, said first arm portion having a plurality of spaced outwardly projecting lugs on either side thereof, means for shifting said breech block between an upper and lower position on said

guide surface, said breech block lugs arranged to engage behind said barrel extension lugs and lock said breech block to said barrel extension until the uppermost lugs on said breech block align with the spaces between the two uppermost lugs on said barrel extension whereupon said barrel extension unlocks from said breech block, and means for arresting said shifting movement of said breech block when said alignment is attained.

10 CLARENCE E. SIMPSON.
